UNITED STATES PATENT OFFICE.

HERVEY H. MCINTIRE, OF SOUTH BEND, INDIANA.

PHOTOGRAPHIC-PRINTING APPARATUS.

SPECIFICATION forming part of Letters Patent No. 784,587, dated March 14, 1905.

Application filed March 29, 1904. Serial No. 200,641.

To all whom it may concern:

Be it known that I, HERVEY H. MCINTIRE, a citizen of the United States, residing at South Bend, in the county of St. Joseph and State 5 of Indiana, have invented certain new and useful Improvements in Photographic-Printing Apparatus; and I do hereby declare the following to be a full, clear, and exact description of the invention, such as will enable 10 others skilled in the art to which it appertains to make and use the same.

This invention relates to improvements in photographic-printing apparatus, and has for its object to provide a machine of this character in which a number of photographs may be printed from the same negative with a uniform exposure, the parts and mechanisms being so arranged as to operate synchronously to avoid overexposure or premature exposure 20 and also being adjustable to regulate or change the period of exposure.

The invention embodies means for controlling a source of light to be emitted on a negative, such means being adjustable to vary the 25 time of exposure and operating simultaneously with a platen which holds the sensitized elements in contact with the negative and which makes its contact instantaneous with the emission of the light, the movements of the platen 30 serving to reset the light-controlling means at each operation of the former.

For a full understanding of the merits and advantages of the present invention reference is to be had to the following description and 35 the accompanying drawings, in which—

Figure 1 is a longitudinal vertical section on the line *a a* of Fig. 2. Fig. 2 is a back view with the back of the case removed, showing the operating mechanism in elevation. Fig. 3 is a front elevation of the upper 40 end of the apparatus, showing the means for setting the light-controlling means and pre-determining the period of operation therefor. Fig. 4 is a transverse section through the case 45 on the line *b b* of Fig. 2, showing a plan view of the operating mechanism. Fig. 5 is a detail, partly in elevation and partly in section, of the light-controlling means and the 50 means for controlling the operation of the same. Fig. 6 is a transverse section on the

line *c c* in Fig. 5, showing the manner of mounting the indicator upon the light-controlling mechanism; and Fig. 7 is a bottom view in elevation of the plunger and its valve, which is carried by the light-controlling mech- 55

Making renewed reference to the drawings, wherein like characters of notation indicate corresponding parts appearing in the several illustrations, and reference being had thereto, 60 1 designates the rear wall of a case or cabinet, 2 the front wall thereof, and 3 an inclined face-board or table having an opening therin which contains a glass 4 and upon which the negative may be supported, or the 65 glass 4 may be dispensed with and the negative fitted directly within the opening, as occasion may require. Beneath the face-board or table 3 is a light-compartment 5, which is separated from the rest of the case by means 70 of the vertical upright wall 6 and a bottom board 7, the upright wall 6 extending to the top of the case and having an opening 8 therein, the purpose of which will appear hereinafter. By this construction it will be seen 75 that the light in the light-compartment 5 is confined therein and that the opening mechanism is in a compartment separate from the light, so that there will be no admission of light into the light-compartment from the 80 opening 8 in the case or from the back of the case if the back board 1 is removed to gain access to the operating mechanism.

A suitable source of light, such as an electric lamp 9, is mounted in the light-compartment and is supplied by means of a conductor *a*, which extends upwardly and connects near the top of the case with a switch 10. The switch consists of a relatively fixed member 11 and a hinged member 12, both of which 85 have suitable binding-posts 13 for connecting with the conductors, the current entering through an opening in the top of the case by the conductor *b* and escaping by means of the conductor *c*, which, as shown in Figs. 1 and 2, 90 is extended down with the conductor *a* to the lamp 9. Secured to the hinged member of contact 12 of the switch is a rod 14, which depends within the case and is pivoted at its lower end to a lever 15, fulcrumed upon an 100

arm 16, that projects from a cross-plate 17, which is fixed to the framework or case of the apparatus. To the free end of this lever 15 is pivoted a dog 18, which is normally in longitudinal alinement with the lever 15 by means of a spring 19. The dog, however, is permitted to tilt upwardly against the action of the spring upon the upward movement of and contact with the timing device, as will be herein-
10 after set forth.

The making and breaking of the circuit in the electric conductors is accomplished by means of the movement of this lever, and its connection 14 with the switch and the means 15 which coöperates therewith for controlling the period of exposure or the time that the light will be emitted upon the negative comprises a rectilinear-movable and rotary adjustable member 20, which in the present instance 20 comprises a drum mounted on a piston-rod 21 and having a portion of its periphery formed with the lugs or projections 22 of different length, the lugs or projections extending longitudinally of the drum and being adapted to 25 be brought into operative position with the dog 18 on the lever 15 in its reciprocating movement. Provision is made for adjusting the drum so as to bring any length lug or projection into alinement with the dog, whereby 30 the latter will be engaged with the drum for a longer or shorter period, as may be required for different exposures. The reciprocating movement of this drum is in a vertical direction, and the downward movement thereof 35 emanates from its weight; but such movement is retarded by means of a cushioning device in the bottom of the case and into which the piston 21 extends. This cushioning device consists of a casing 23, which may contain a 40 fluid—such as air, gas, or water, &c.—and on the end of the piston is a plunger 24, provided with a plurality of openings 25 and also having depending lugs or keepers 26, between which and the plunger is loosely fitted a check- 45 valve 27, which upon the descent of the drum and the plunger closes the openings 25 and prevents the fluid beneath the plunger from escaping through the openings to the upper side of the plunger. In order to provide for 50 a gradual descent of the plunger, the end of the piston-rod is provided with a duct 28, which may be said to be capillary, so as to permit a limited amount of the fluid to pass therethrough, so as the plunger may descend 55 slowly. A suitable central opening is formed in the valve and adapted to aline with the duct 28, as shown in Fig. 5. A means for graduating or controlling the flow of liquid to the upper side of the plunger upon the descent 60 thereof may be provided by a rotary adjustable valve, which forms the subject-matter of a copending application filed on August 3, 1903, and bearing Serial No. 168,054; but such a valve may not of necessity be utilized, 65 as the construction shown in the present in-

vention may be sufficient. Upon the upward movement of the drum and plunger carried thereby the fluid will escape to the under side thereof through the openings 25, as the valve will be relieved of the pressure on the under 70 side and become unseated from the plunger, but will be held suspended therefrom by means of the keepers 26.

For the purpose of imparting a rotary movement to the drum, so as to bring any of the 75 projections 22 thereon into alinement with the dog 18, the upper end of the piston-rod, which projects above the drum, is squared and fitted with a bushing 29, which is journaled in a sleeve 30. The sleeve is secured to an arm of 80 a standard 31, which is mounted on a transverse shelf 32 in the case, and to the other side of this standard is secured a plate 33, which extends forwardly through the opening 8 in the front of the case and has its front 85 face formed into a segment which provides a dial 34. This dial is provided with a plurality of apertures 35, and beneath the apertures are numbers or characters which correspond with the number of projections 22 on the 90 drum 20 and by means of which the time of the descent of the drum may be predetermined. Secured to or integrally formed on the bushing 29 is an indicator-arm 36, provided with a spring catch or pin 37, which is adapted to 95 engage in any one of the apertures 35 on the dial, so as to set the light-controlling drum for different periods of exposure.

From the description thus far given it will be observed that the emission of the light is 100 controlled by means of the drum 20, which during its descent engages with the dog 18 of the lever 15 and trips the latter, so as to force the outer end thereof upwardly, and through the connection 14 the contact member 12 will be brought into engagement with the member 10 of the switch, thereby 105 making the circuit and emitting the light, and that upon the upward movement of the drum the lever 15 will be tilted and the connection 14 drawn downwardly to break the contact, and this is permitted without any undue strain upon the lever and its connecting-rod by virtue of the spring-pressed dog, which is permitted to yield against the action 110 of the spring and be tilted upwardly, as shown in dotted lines in Figs. 1 and 5. It will also be seen that when it is desired to change the time of exposure the drum 20 may be rotated by means of the indicator-arm 36, which 115 has a fixed engagement with the piston-rod of the drum, and this rotation will bring a different lengthed lug or projection 22 into alinement with the dog 18 of the lever, so that the lever will be tripped and the contact made for 120 just such a period as may be required to print the picture, it being understood that each of the members or characters on the dial corresponds to the units of time that the particular projection which has been brought 125 130

in alinement with the dog will be in engagement therewith, so that if a four-second exposure is required the indicator-arm is set and the spring-catch engaged in the aperture over 5 the numeral "4" and the fourth lug, beginning from the shortest one on the drum, will be in alinement with the pawl.

The present invention in addition to the means for controlling the emission of light, as 10 above explained, embodies mechanism for resetting the light-controlling means and mechanism for synchronizing the contact of the platen which carries the sensitized element with the light source, together with means operating to automatically retain the light-controlling drum in an operative position, the 15 said last-named means being operated upon by the platen-operating means to release the light-controlling drum and permit it to operate. These several means and mechanisms 20 are controlled by the movement of a hand-lever 38, which is secured to a rock-shaft 39, fulcrumed in the bottom of the case, as at 40, and on the end of this rock-shaft is an arm 25 41, which connects with one arm of a bell-crank lever 42 by means of a link 43, and the other arm, 44, of the bell-crank lever is pivotally secured to a rod 45, which extends 30 upwardly and has its upper end pivoted to the cross-bar 46 of a platen-frame 47. The platen-frame has two forwardly-projecting 35 arms 48 at each side thereof, and these arms are stayed or braced at an intermediate point by a cross-head 49, the ends of which project beyond the sides of the arms to provide 40 pintles, which are pivoted in bracket-arms 50. The bracket-arms 50 project from the front 45 of the standard 31 through the opening 8 in the front of the case, so that the platen 51, carried by the ends of the platen-arms, may 50 have a free swinging movement on the outside 55 of the case above the face-board 3, while the platen-frame is confined within the case and is moved up and down to vibrate the platen 60 by means of the movement of the rod 45 and its connection with the hand-lever 38. It will 65 thus be seen that the lever 38 controls the raising and lowering of the platen 51, and all the other mechanisms, such as the light-controlling mechanism and the resetting means 70 for the light-controlling mechanism, are in turn controlled by the platen-frame.

Pivoted to the cross-bar 46 of the platen-frame and depending therefrom is a link 52, the lower end of which is pivoted to a lever 53, fulcrumed upon an arm 54, which projects 75 downwardly from the cross-plate 17, and on the end of this lever is a roller 54^a, which is adapted to engage with the bottom of the 80 light-controlling drum 20 when the latter is elevated, and its elevation takes place upon the downward movement of the platen-frame, which rocks the lever 53, through the link connection 52, on its fulcrum and forces the 85 free end, carrying the roller, upwardly, to the

position shown in dotted lines in Fig. 1. The light-controlling drum is held in an elevated position by a swinging dog 55, pivotally hung on an arm 56, which is secured to the standard 31, and the upper end of this dog projects upwardly into the path of an adjustable pin 57, carried by the cross-bar 46 of the platen-frame. 70

As shown by dotted lines in Fig. 1, the swinging dog 55 is engaged with the bottom 75 of the light-controlling drum, and the platen-frame is lowered, so that the adjustable pin 57 is out of engagement with the upper end of the dog; but upon the upward movement of the platen-frame and the contact of the platen with the negative the adjustable pin 57 contacts with the upper end of the dog and trips the latter to disengage the lower end thereof from the light-controlling drum, as shown in 80 full lines in Fig. 1, so that the drum will be 85 permitted to descend and trip the spring-dog 18 on the end of the lever 15, which prior to the descent of the drum is directly beneath the same, as shown in dotted lines in Fig. 1, but which when engaged therewith will, 90 through the connection 14, make the contact of the electric switch to emit a light upon the negative, as before explained.

On the side of the case is a guide 58, which may have a suitable notch 59 near one end 95 thereof onto which a pawl or lug carried by the lever 38 may be engaged to hold the platen-frame elevated and the platen lowered during the printing operation.

Assuming that the parts are in the position 100 shown in full lines in Fig. 1, with the platen-frame raised and the platen lowered and the light-controlling drum lowered to the limit of its downward movement, which latter position is indicated in dotted lines in Fig. 1, and 105 it is desired to print pictures from a negative which has previously been positioned upon the face-board, the hand-lever 38 is released from its engagement with the notch 59 in the 110 guide 58 and pulled forwardly. This forward movement of the lever will lower the arm 44 of the bell-crank lever and draw the rod 45 downwardly, lowering the platen-frame, which by the link connection 52 will push one 115 end of the lever 53 downwardly and raise the other end thereof, the roller contacting with the bottom of the light-controlling drum and elevating that element to the position shown 120 in dotted lines at the top in Fig. 1. During the upward movement of the light-controlling drum the spring-dog 18, carried by the lever 15, will be tilted upwardly by its engagement 125 with the drum, and such movement will maintain the switch 10 in an open position, which is indicated in dotted lines in Fig. 1. When the light-controlling drum has reached the limit of its upward movement, the swinging dog 55 engages beneath the drum and holds it elevated. With the parts in this position the platen 51 is elevated, and the sensitized ele- 130

ment on which the picture is printed may be placed upon the negative or fixed to the platen preparatory to the contact thereof. Now by pushing the hand-lever 38 back the position 5 of the parts is reversed, the platen-frame being elevated and the platen lowered to make the contact, and the lifting-lever 53 is also disengaged from the bottom of the drum. As the platen-frame reaches the limit of its up- 10 ward stroke the adjustable pin 57, carried thereby, will contact with the end of the swinging dog 55 and disengage the lower end thereof from the light-controlling drum and permit that element to descend, which, as be- 15 fore stated, is retarded in its downward movement by means of the cushioning device located in the bottom of the case. Simultaneously with the release of the light-controlling drum the spring-pawl 18 on the end of the lever 15, 20 which has previously been extended into alignment with the lever by means of the spring, will be engaged with one of the projections 22 on the drum, and the outer end of this lever will be pushed upwardly to make the con- 25 tact at the switch, thereby completing the circuit and emitting a light upon the negative. During the descent of the drum the lever 15 remains in this position until the end of the projection 22 with which it is engaged is 30 reached, when the spring-dog 18 will be free from contact with any portion of the drum, and the weight of the lever 15, the connecting-rod 14, and the hinged contact 12 will cause the circuit to be broken, whereupon the 35 light will be extinguished, and although the drum may continue to descend it will not affect the exposure, because the switch-lever 15 cannot be tripped again to make the contact until the drum is again elevated. It will 40 therefore be seen that an overexposure is prevented, and the device may be left unattended without destroying the picture. Upon the next forward throw of the lever the platen will be raised, and the operator may remove 45 the sensitized element and replace it by another and continue the printing operation as required.

To assist the operator in restoring the light-controlling drum to operative position, the 50 cross-bar 46 at the rear end of the platen-frame has a pair of weights 59 suspended therefrom, and these weights may be heavy enough to automatically restore the parts to 55 operative position when the hand-lever is dis- 55 engaged from the notch 59 in the guide 58, and in such case they would have to counter- 60 balance the weight of the drum and the friction between the parts of the operating mechanism.

60 I claim—

1. A photographic-printing apparatus pro- 65 vided with a movable platen, means for man- 70 ually operating the platen, and means con- 75 trolled by the movements of the platen for

emitting a light to a negative and for resetting 65 the light-emitting means.

2. A photographic-printing apparatus pro- 70 vided with a movable platen, means for man- 75 ually operating the platen, means for control- 80 ling the admission of a light to a negative for 85 a predetermined period, and means operated by the platen for resetting the light-control- 90 ling means.

3. A photographic-printing apparatus pro- 95 vided with a movable platen, means for oper- 100 ating the platen, means co-operating with the platen-operating means for emitting a light to a negative for a predetermined period, and means operated by the movements of the platen for resetting the light-emitting means. 80

4. In a photographic-printing apparatus, a case having a source of light therein and pro- 85 vided with means for holding a negative and a sensitized element, a platen, means for man- 90 ually operating the platen, means for emitting 95 a light to the negative, and means operated by the platen-operating means for restoring the light-emitting means into operative posi- 100 tion.

5. In a photographic-printing apparatus, a 90 case having a source of light therein and pro- 95 vided with means for holding a negative and a sensitized element, a movable platen, means for manually operating the platen, means for emitting a light to the negative for a prede- 100 termined period, said means operating simul- 105 taneously with the contact of the platen, means controlled by the movement of the platen for resetting the light-emitting means, and means operated by the platen-operating means for 110 releasing the light-emitting means.

6. In a photographic-printing apparatus, a case having a source of light therein and pro- 105 vided with means for holding a negative and a sensitized element, a movable platen, a 110 platen-frame movable with the platen means connected with the platen-frame for operating the platen, a movable member for controlling the emission of light to the negative, means carried by the platen-frame and operating 115 simultaneously with the contact of the platen to release the light-emitting means, and means operated by the platen-operating means for bringing the said movable element into operative position.

7. A photographic-printing apparatus pro- 115 vided with a movable platen, means for oper- 120 ating the platen, comprising a platen-frame, a hand-lever, connections between the platen- 125 frame and the hand-lever, means for emitting a source of light to the negative, and means for controlling the admission of the light for a predetermined period.

8. In a photographic-printing apparatus, a case having a source of light therein and pro- 125 vided with means for holding a negative and a sensitized element, a platen, a platen-frame movable with the platen, mechanism connected

with the platen-frame for operating the platen, a movable member for controlling the emission of light to the negative, means for setting said member to predetermine the period of exposure, and means operated by the movement of the platen-frame for controlling the operation of the movable element.

9. In a photographic-printing apparatus, a case having a source of light therein and provided with means for holding a negative and a sensitized element, a movable platen, a platen-frame movable with the platen, means connected with the platen-frame for manually operating the platen, a movable member for controlling the emission of light to the negative, means for operating upon said member for predetermining the period of exposure, means operated by the platen-operating means for bringing the movable elements into operative position, and means carried by the platen-frame, operating simultaneously with the contact of the platen, to release the movable member.

10. In a photographic-printing apparatus, a case having a source of light therein and provided with means for holding a negative and a sensitized element, a platen, a platen-frame movable with the platen and disposed in the case, a hand-lever, connections between the platen-frame and the hand-lever for operating the platen, a vertically-reciprocatory drum in the case, a cushioning device in the case to regulate the descent of the drum, means formed on the drum for controlling the admission of light to the case for a predetermined period, a lever operated by the platen-operating means for elevating the drum, means for holding the drum in an elevated position, and means carried by the platen-frame and operating on the drum-holding means simultaneously with the contact of the platen to release the drum.

11. In a photographic-printing apparatus, a case having a source of light therein and provided with means for holding a negative and a sensitized element, a platen, a platen-frame movable with the platen, a hand-lever, jointed connections between the hand-lever and the platen-frame for operating the platen, a vertically-movable drum having a plurality of projections of different length upon its periphery, means beneath the drum for retarding the descent thereof, an electric switch, a contact-lever arranged within the path of the projections on the drum and connected with the switch to make and break an electric circuit to emit light to the negative, means operated by the platen-frame for elevating the drum, a dog for holding the drum elevated, means carried by the platen-frame to trip the dog to release the drum, means for adjusting the drum to bring one of the projections thereon into the path of the switch-lever, and means coöperating with the last-named means for predetermining the period of contact between

the switch-lever and the projections on the drum.

12. A photographic-printing apparatus provided with a manually-operated platen, a platen-frame for the platen, a reciprocatory member, a dog engaging said member to hold it elevated, means carried by the platen-frame adapted to trip the dog and release the reciprocatory member, an electric switch operated by the reciprocatory member, and an electric lamp connected to the switch. 75

13. In a photographic-printing apparatus, a platen, a platen-frame, a reciprocatory member controlled by the movements of the platen-frame, a switch controlled by the reciprocatory member, and a lamp connected with the switch. 80

14. In a photographic-printing apparatus, a platen, a platen-frame, a reciprocatory member, means to hold the reciprocatory member elevated, means carried by the platen-frame 85 to engage the first-mentioned means and release the reciprocatory member, means connected with the platen-frame to elevate the reciprocatory member, and an electric-lighting circuit controlled by the reciprocatory member. 90

15. In a photographic-printing apparatus, a platen, a platen-frame, a reciprocatory member, means to hold the reciprocatory member elevated, means carried by the platen-frame 95 to engage the first-mentioned means and release the reciprocatory member, a lifting-lever connected with the platen-frame and adapted to elevate the reciprocatory member, and an electric-lighting circuit controlled by the reciprocatory member. 100

16. In a photographic-printing apparatus, a movable platen, a platen-frame movable therewith, means connected with the platen-frame for operating the platen, a reciprocatory member controlled by the movements of the platen-frame, and an electric-lighting circuit controlled by the reciprocatory member. 105

17. In a photographic-printing apparatus, a movable platen, a platen-frame movable therewith, means connected with the platen-frame for operating the platen, a reciprocatory member controlled by the movements of the platen-frame, a lever 15 adapted to engage the reciprocatory member, an electric switch connected 110 with said lever, a lamp, an electric circuit connecting the switch and lamp, and means for adjusting said reciprocatory member to change the period of contact with the lever. 115

18. In a photographic-printing apparatus, a movable platen, a platen-frame movable therewith, means connected with the platen-frame for operating the platen, a reciprocatory member controlled by the movements of the platen-frame, a lever 15 adapted to engage the reciprocatory member, an electric switch connected 120 with said lever, a lamp, an electric circuit connecting the switch and lamp, means for adjusting said reciprocatory member to change the period of contact with the lever. 125

justing said reciprocatory member to change the period of contact with the lever, and a scale to predetermine the period of contact.

19. In a photographic-printing apparatus, a movable platen, a platen-frame movable therewith, means connected with the platen-frame for operating the platen, a reciprocatory member controlled by the movements of the platen-frame, a lever 15 adapted to engage the reciprocatory member, an electric switch connected with the said lever, a lamp, an electric circuit connecting the switch and lamp, means for changing the period of contact between the lever 15 and the reciprocatory mem-

ber comprising a plurality of projections of 15 different length on the reciprocatory member with which the lever contacts, a guide-rod non-rotatable in the reciprocatory member, and an indicator-arm rigid on the guide-rod, and a scale over which the indicator moves, substantially as specified. 20

In testimony whereof I affix my signature in presence of two witnesses.
